TRAFFIC PROTECTION APPARATUS

John H. Broadbent, Willistown Township, Chester County, Pa., assignor to The Union Switch and Signal Company, Swissvale, Pa., a corporation of Pennsylvania

Application April 25, 1946, Serial No. 664,717

8 Claims. (Cl. 246—114)

1

My invention relates to traffic protection apparatus, and particularly to apparatus for providing crossover protection for trains moving along railway tracks which are connected with each other by a crossover track through hand-operated track switches.

A requisite for crossover protection apparatus is that it must be so arranged that a car or locomotive while occupying a crossover such, for example, as one connecting two main tracks, while the switches are in the normal position for train movements along the main tracks, will cause a signal for each main track to indicate stop if the car or locomotive is within fouling distance of that main track. In crossover protection schemes embodying track circuits, one characteristic should therefore be high shunting sensitivity in order to insure that the crossover track circuits will be shunted if the crossover track has high contact resistance due to infrequent train movements over the crossover.

One feature of my invention is the provision of low frequency alternating current track circuits in which the voltage may be arranged to be sufficiently high to provide good shunting sensitivity. These track circuits are also so arranged as to provide protection against defective insulated rail joints.

A further feature of my invention is the provision of means controlled by a coding device for supplying low frequency alternating current to the rails of one of two sections of a crossover track, and of means also controlled by the coding device for rectifying alternating current energy received from the other track section for controlling traffic governing means.

I shall describe one form of apparatus embodying my invention, and shall then point out the novel features thereof in claims.

The accompanying drawing is a diagrammatic view showing one form of apparatus embodying my invention.

Similar reference characters refer to similar parts in the drawing.

Referring to the drawing, a stretch of railway is shown comprising two parallel tracks, designated by the reference characters 1T and 2T, connected with each other by a crossover track designated by the reference character 3T, through hand-operated switches 1W and 2W. Track 3T is divided, by means of insulated joints 4, into two sections a—b and b—c.

A coding device designated by the reference character CT is constantly energized by a suitable source of current, not shown, but having

2

terminals designated B and N. Device CT may have an operating frequency of 180 cycles per minute, for example, at which it moves each of its contacts 5 and 8 between a first position and a second position in which, as here shown, it connects with front and back points, respectively.

Contact 5 of coding device CT, while being operated between its front and back points, controls repeated energization of primary winding m of a transformer, designated by the reference character 1F, alternately in opposite directions. Secondary winding d of transformer 1F is connected across rails 3a and 3b of section b—c, to which it supplies low frequency alternating current.

A second transformer 2F has a primary winding m connected across the rails of section b—c, and a secondary winding d connected across the rails of section a—b. This transformer therefore transmits alternating current energy from section b—c to section a—b, but at the same time prevents the flow of direct current between these sections.

A decoding transformer 3F has a primary winding m which is energized by current received from section a—b. The current output from secondary winding d of transformer 3F is rectified by contact 8 of coding device CT while this contact is being operated between its front and back points.

A slow pick-up slow release code detecting relay RP is energized by this rectified current. Contacts 11 and 12 of relay RP, as here shown, control traffic governing means for tracks 1T and 2T.

As shown in the drawing, all parts of the apparatus are in the normal condition, that is, switches 1W and 2W are in the normal position; coding device CT is constantly energized, and hence its contacts 5 and 8 are being repeatedly closed alternately at their front and back points at a given suitable frequency such for example as 180 cycles per minute; primary winding m of transformer 1F is repeatedly energized alternately in opposite directions in response to the operation of contact 5; secondary winding d of transformer 1F is therefore supplying low frequency alternating current to the rails of section b—c, and hence transformers 2F and 3F in turn are energized. The current output from secondary winding d of transformer 3F is being rectified by contact 8 of coding device CT; and relay RP is therefore energized and its contacts 11 and 12 are closed in signal control circuits for tracks 1T and 2T.

Each time contact 5 of coding device CT closes

at its front point, a circuit is closed, passing from terminal B, through the front point of contact 5 of coding device CT, and portion 6 of primary winding *m* of transformer 1F to terminal N. Each time contact 5 closes at its back point, a similar circuit is closed which energizes portion 7 of primary winding *m* of transformer 1F in the opposite direction.

Low frequency alternating current is therefore generated in secondary winding *d* of transformer 1F. This current is supplied, by winding *d*, to the rails of section *b*—*c*, and energizes primary winding *m* of transformer 2F. Low frequency alternating current is therefore also generated in secondary winding *d* of transformer 2F. This current is supplied by transformer 2F to the rails of section *a*—*b*, and energizes primary winding *m* of decoding transformer 3F.

Contact 8 of coding device CT closes at its front and back points at the same times that contact 5 closes at its front and back points, respectively. Contact 8, connected as shown, therefore rectifies the current output from secondary winding *d* of transformer 3F. Relay RP is energized by this rectified current, and hence its contacts 11 and 12 are closed in signal control circuits for tracks 1T and 2T, respectively.

When a train occupies crossover track 3T anywhere within fouling distance of track 1T or 2T, the track circuit for one or the other of the sections *a*—*b* and *b*—*c* will be shunted, and hence transformer 3F will be deenergized. Relay RP will therefore also be deenergized, and hence its contacts 11 and 12 will be opened, causing the signals for both tracks 1T and 2T to indicate stop.

Some of the advantages provided by apparatus embodying my invention are as follows:

1. *Fouling protection.*—A train occupying crossover 3T at any point within fouling distance of tracks 1T and 2T will cause the signals for tracks 1T and 2T to indicate stop.

2. *Superior shunting sensitivity.*—Transformers 1F and 2F can be arranged to supply high enough voltages to the rails of sections *b*—*c* and *a*—*b*, respectively, to break through high contact resistance which might occur due to infrequent use of the crossover track.

3. *Broken rail protection.*—All portions of the track rails included in the track circuits for crossover track 3T are in series, and hence the best possible broken rail protection is provided.

4. *Foreign current protection.*—A high degree of immunity to foreign current is provided.

5. *Protection against defective insulated joints.*—If the insulated joint at *a* in rail 3a should break down, a track circuit, not shown, for track 1T would be deenergized. If the insulated joint at *a* in rail 3b should break down, transformer 3F would be shunted. If the insulated joint in rail 3a at point *b* should break down, and if there should be a current leak from rail 2a of track 2T to rail 1a of track 1T, tending to connect winding *d* of transformer 1F across the rails of track 1T, the successive reversals of polarity of the current from the secondary winding of transformer 1F would prevent operation of a track relay for track 1T by current from transformer 1F. If the coding device CT should fail, and its contacts should stick in either position, primary winding *m* of transformer 1F would be constantly energized in one direction, and hence its secondary winding *d* would be deenergized.

Although I have herein shown and described only one form of apparatus embodying my invention, it is understood that various changes and

modifications may be made therein within the scope of the appended claims without departing from the spirit and scope of my invention.

Having thus described my invention, what I claim is:

1. In combination, a stretch of railway track divided into two sections, a coding device having two contacts repeatedly closed at the same time alternately in a first position and a second position while said coding device is energized, a transformer, a secondary winding of said transformer connected across the rails of one of said sections adjacent one end of said stretch of track, means controlled by one of said contacts in its first and second positions for repeatedly energizing the primary winding of said transformer alternately in opposite directions, a second transformer the primary winding of which is connected across the opposite end of said one track section and the secondary winding of which is connected across the adjacent end of the other track section, a decoding transformer the primary winding of which is connected across the opposite end of said other track section, a code detecting relay, means including the other one of said contacts for rectifying the current from the secondary winding of said decoding transformer for energizing said code detecting relay, and traffic governing means controlled by said code detecting relay.

2. In combination, a stretch of railway track divided into two sections, a coding device having two contacts repeatedly closed at the same time alternately in a first position and a second position while said coding device is energized, means controlled by one of said contacts while being operated to its first and second positions for supplying low frequency alternating current across the rails of one of said sections, means for transmitting alternating current energy and at the same time obstructing the flow of direct current from said one section to the other section, a decoding transformer the primary winding of which is connected across the rails of said other section, means including the other one of said contacts for rectifying the current output from the secondary winding of said decoding transformer, and traffic governing means controlled by said rectified current.

3. In combination, a stretch of railway track divided into two sections, a cooling device having two contacts repeatedly closed at the same time alternately in a first position and a second position while said coding device is energized, means controlled by one of said contacts while being operated to its first and second positions for repeatedly supplying current of alternately normal and reverse polarity to the rails of one of said sections, a transformer the primary winding of which is connected across the rails of said one section and the secondary winding of which is connected across the rails of the other section, a decoding transformer the primary winding of which is energized by alternating current energy from the rails of said other section, means including the other one of said contacts for rectifying the current output from the secondary winding of said decoding transformer, and traffic governing means controlled by said rectified current.

4. In combination, a stretch of railway track divided into two sections, a coding device, means controlled by said coding device for supplying low frequency alternating current to the rails of one of said sections, means for transmitting al-

ternating current energy and at the same time obstructing the flow of direct current from said one section to the other section, a decoding transformer the primary winding of which is energized from the rails of said other section, means controlled by said coding device for rectifying the current output from the secondary winding of said decoding transformer, and traffic governing means controlled by said rectified current.

5. In combination, a stretch of railway track divided into two sections, a coding device, a transformer the secondary winding of which is connected across the rails of one of said sections, means controlled by said coding device for repeatedly energizing the primary winding of said transformer alternately in opposite directions, means for transmitting alternating current energy but at the same time obstructing the flow of direct current from said one section to the other section, a decoding transformer the primary winding of which is energized from the rails of said other section, means controlled by said coding device for rectifying the current output from the secondary winding of said decoding transformer, and traffic governing means controlled by said rectified current.

6. In combination, a pair of conductors divided into two sections, a coding device, means controlled by said coding device for repeatedly supplying current of alternately normal and reverse polarity to the conductors of one of said sections, means for transmitting alternating current energy but at the same time obstructing the flow of direct current from said one section to the other section, means controlled by said coding device for rectifying alternating current energy received from the conductors of said other

section, and electrical control means controlled by said rectified energy.

7. In combination, a section of railway track, a coding device, means controlled by said coding device for repeatedly supplying current of alternately normal and reverse polarity to the rails of said section, a decoding transformer the primary winding of which is energized from said section, means controlled by said coding device for rectifying the current output from the secondary winding of said decoding transformer, and traffic governing means controlled by said rectified current.

8. In combination, a section of railway track, a coding device, means controlled by said coding device for repeatedly supplying current of alternately normal and reverse polarity to the rails of said section, a decoding transformer, means controlled by current received from said section for energizing the primary winding of said decoding transformer, means controlled by said coding device for rectifying the current output from the secondary winding of said decoding transformer, and traffic governing means controlled by said rectified current.
